RECEPTACLE FOR CLIPPER

Vincent Giuliana, Springfield, Mass.

Application May 12, 1950, Serial No. 9,911

Term of patent 7 years

(Cl. D4—3)

To all whom it may concern:

Be it known that I, Vincent Giuliana, a citizen of the United States, residing at Springfield, in the county of Hampden, and Commonwealth of Massachusetts, have invented a new, original, and ornamental Design for Receptacle for Clipper, of which the following is a specification, reference being had to the accompanying drawings, forming part hereof:

Fig. 1 is a plan view of a receptacle for clipper showing my new design;

Fig. 2 is a side elevational view;

Fig. 3 is a front elevational view;

Fig. 4 is a sectional elevational view on the line 4—4 of Fig. 1; and

Fig. 5 is a rear elevational view.

I claim:

The ornamental design for a receptacle for clipper, as shown.

VINCENT GIULIANA.
